United States Patent Office.

E. S. EARLEY, OF PHILADELPHIA, PENNSYLVANIA.

Design No. 2,698, dated July 9, 1867.

DESIGN FOR A BURIAL-CASE OR COFFIN.

The Schedule referred to in these Letters Patent and making part of the same.

TO ALL WHOM IT MAY CONCERN:

Be it known that I, E. S. EARLEY, of the city and county of Philadelphia, and State of Pennsylvania, have invented a new and useful Design for Burial Caskets or Coffins; and I do hereby declare the following to be a clear and exact description of the nature thereof, sufficient to enable others skilled in the art to which it appertains to fully understand and use the same, reference being had to the accompanying drawings, making part of this specification, in which—

Figure 1 is a side elevation of a burial case constructed according to my design.

Figure 2 is a top view thereof.

My invention consists in a burial casket or coffin of beautiful design and form.

The body A of the coffin has its sides *a* parallel with oblique extensions, which unite with the head and foot pieces B C, so that the corners present the appearance of being "cut off," as shown at *b*. A bead, *c*, is placed around the body at the bottom thereof, and at equal distances from the top and bottom of the body I place beads *d e*. Suitable buttons or studs *f* are placed on both sides of the joints, between the oblique extensions and the bead and foot pieces, and also around the body between the beads *c* and *e*. D is the lid or cover of raised form, and may be said to resemble a truncated oblong pyramid. The raised part is moulded, the members of which moulding are a cove, *g*, fillet, *h*, ovoli, *i*, and fillet, *k*, and the ends of the cover are beaded, as shown at *l*. The top *m* of the lid is flat, and may be provided with a suitable shield or plate. The shape of the lid is similar to the body of the coffin, that is, it has its corners "cut off," and the moulding conforms thereto. Buttons or studs *n* are placed at various points, which, with screw heads *o*, should be plated. Ordinary handles may be placed at proper points of the body, the form of which may be varied.

Having thus described my invention, what I claim as new, and desire to secure by Letters Patent, is—

The design for burial cases, substantially as described and represented in the drawings.

To the above I have signed my name this 10th day of June, 1867.

E. S. EARLEY.
